J. R. KERNS,
MOTOMETER LAMP,
APPLICATION FILED NOV. 8, 1920.

1,386,179.

Patented Aug. 2, 1921.

Inventor
John R. Kerns,
By Arthur H. Ewald,
Ottawa, Ontario

UNITED STATES PATENT OFFICE.

JOHN R. KERNS, OF COVINGTON, KENTUCKY.

MOTOMETER-LAMP.

1,386,179.

Specification of Letters Patent. Patented Aug. 2, 1921.

Application filed November 8, 1920. Serial No. 422,437.

To all whom it may concern:

Be it known that I, JOHN R. KERNS, a citizen of the United States, and resident of Covington, in the county of Kenton and State of Kentucky, have invented certain new and useful Improvements in Motometer-Lamps, of which the following is a full, clear, and exact description, reference being had to the accompanying drawings, forming a part of this specification.

My invention relates to lamps for illuminating the motometer of an automobile so that the same is visible at night.

The location of the motometer on the radiator cap of an automobile, which is, of course necessary, in order that it may operate for the purpose designed, is such that its visibility is at most times more or less difficult, and this difficulty under faulty conditions of light becomes so great as to impair absolutely the utility of the device as few drivers will take the time and trouble to leave the vehicle and light the motometer artificially to obtain a reading. The principal object of the present invention is to overcome this difficulty and to provide a lamp which is so located and adjusted as to be at all times available for the purpose of illuminating the instrument.

A further object of this invention is to provide in connection with a lamp suitable for the illumination of a motometer, an adjustable mounting for said lamp.

Other objects of the invention will appear from the following detailed description thereof.

In the drawings:

Figure 1 is a side elevation of the invention illustrating its mounting and use;

Fig. 2 is a central longitudinal view of the lamp;

Fig. 3 is a front elevation of the invention as illustrated in Fig. 1, part of the motometer being broken away to disclose features of the lamp mounting;

Fig. 4 is a perspective of a modified mounting of the lamp standard on the radiator cap.

The numeral 1 illustrates the radiator cap of an automobile, and 2 a motometer mounted on said cap in the usual manner.

Secured between the lower portion of the motometer and the lock nut 3 thereof is an arm 4 upon the outer end of which a tubular standard 5 is secured by means of a nut 6. 55 Arranged to telescope in the standard 5 is a rod 7 upon the free end of which a ring or head 8 is secured or integrally formed if desired. A set screw 9 secures the rod 7 in the standard 5 at the desired elevation. 60

Arranged to fit in the head 8 is a lamp barrel or socket 10, which is provided with the usual electrical connections for an ordinary plug 11 and bulb 12. The front or lamp end of the socket 10 is externally threaded 65 to receive a lamp shroud or guard 13 of ordinary construction. The socket is adjustable, both longitudinally and rotatably in the head 8, and arrangement is made to secure it in desired adjustment by means of a set 70 screw 14.

In Fig. 4 I have illustrated a modified form of attachment of the standard 5 by means of rivets or bolts which secure it directly to the radiator cap. 75

From the foregoing description the nature and value of the present invention will be fully apparent to those familiar with the art to which the same appertains. When a motometer lamp of the kind described is 80 provided in connection with the instrument, it will be seen that provision is made for the suitable illumination of the device at all times and under all conditions. By means of the vertical adjustments provided for in 85 the tubular standard 5 and telescoping rod 7 provision is made whereby the lamp may be adapted to meters of various size, and the adjustability of the barrel or socket 10 in the head 8 both longitudinal and rotary enable the operator to adjust the lamp so that 90 its beams are thrown directly on the face of the instrument.

It will be understood that various modifications in the details of construction described may be made without departing from the invention as above defined and as set forth in the appended claim. 95

Having thus fully described my invention, what I claim as new and desire to secure by Letters Patent, is:

A motometer lamp, comprising in combi-

nation with a motometer, a tubular standard mounted adjacent said motometer, a rod arranged to telescope in said standard, a set screw to secure said rod in desired adjustment in the standard, an annular head on the free end of said rod, a socket arranged to fit in said head and to be longitudinally

and rotatably adjustable therein, a set screw to secure said socket in desired adjustment; said socket being arranged to receive an 10 electrical bulb and an electrical plug, and electrical connections in said socket between said plug and bulb.

JOHN R. KERNS.
